Primary Examiner — Dana L Meyrow(74) *Attorney, Agent, or Firm* — Nixon & Vanderhye, PC(57) **CLAIM**

The ornamental design for a glass container, as shown and described.

DESCRIPTION

FIG. 1 is a top, front perspective view of a glass container showing my new design;

FIG. 2 is a front elevation view thereof, the rear elevation being the same excluding the unclaimed thread elements;

FIG. 3 is a top plan view thereof; and,

FIG. 4 is a bottom plan view thereof.

All surfaces shown in broken lines form no part of the claimed design.
